PARTITION CONSTRUCTION

Gilbert L. Fowles, Lakewood, and Charles J. No-car, Cleveland, Ohio, assignors to The E. F. Hauserman Company, Cleveland, Ohio, a corporation of Ohio

Application August 4, 1940, Serial No. 351,383

11 Claims. (Cl. 189—34)

In sheet metal partitions, particularly of the relatively thin space-saving form, and involving spaced-apart face plates, it is sometimes a matter of difficulty to obtain desirably close fitting joints between face plates of adjacent sections. Prevalent constructions also have not afforded all the space desired for pipes and like bulky placements in addition to wiring. Generally also there has been a lack of adequate means for taking care of sagging in sections including door frame elements. In accordance with the present invention, a construction may be had providing the desired features of space-saving walls, and avoiding disadvantages as heretofore noted.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative however, of but a few of the various ways in which the principle of the invention may be employed.

In said annexed drawings:

Fig. 1 is a front elevational view of a portion of wall illustratively including a door and typical panel sections; Fig. 2 is a fragmentary horizontal section, enlarged, taken on a plane substantially indicated by the line II, Fig. 1; Fig. 3 is a fragmentary elevational detail of the upper corners of adjacent panel sections; Fig. 4 is a perspective view of the corner bracket member thereof; Fig. 5 is a perspective view of a reinforcing member on the inside of the panel face member; Fig. 6 is a perspective view of the lower corner of a panel floor support; Fig. 7 is a fragmentary rear elevational view of the flange of a channel vertical support member, showing a locking lug on the reinforcing member in engagement therewith; Fig. 8 is a fragmentary horizontal section looking downwardly, taken just above the lower horizontal edges of the panels 3; Fig. 9 is a fragmentary elevational detail of the upper right corner of the portion adjacent the door shown in Fig. 1; Fig. 10 is a fragmentary vertical section taken on a plane substantially indicated by line X—X, Fig. 9; Fig. 11 is a fragmentary horizontal section taken on a plane substantially indicated by line XI—XI, Fig. 9; Fig. 12 is a fragmentary horizontal section of Figs. 1 and 9; Fig. 13 is a fragmentary elevational view of the web of an auxiliary support or a door frame support; Fig. 14 is a vertical section taken on line XIV—XIV of Fig. 1; and Fig. 15 is a perspective view of a modification of the lat-

ter where a panel does not extend entirely to the ceiling.

The wall or partition is in general assembled of panel sections, which may be prepared at the factory and require merely securing together at the place of construction. Thus, a panel section may comprise vertical supports S, such as of channel form, and having their webs 2 directed back to back in the section, see Fig. 2, thereby leaving the channel open at the edge until closed up by the positioning of the adjacent member. In such form it will be noticed that there is no outside seam-covering or joint-covering member capable of concealing loosely-closed joints, and an important advantage of the present construction is its ability to attain precision jointing on the exposed faces irrespective of the inequalities primarily encountered in open joint construction. Spaced-apart panel face members 3 provide the wall-finish, and these may be of suitable gauge sheet metal, inwardly flanged as at 4, and having a rebend 5. Each face member is fastened to the vertical support independently and adjustably horizontally and vertically, each face member being provided with corner-brackets B within its corners, these brackets, as shown in detail in Fig. 4, having wings 7, 8, at right angles to each other, the bracket being welded or otherwise secured to the inside of the face member and such as to project beyond, to expose the bolt holes, as shown in Fig. 3 for the upper brackets, and in Fig. 6 for the lower brackets. In such positioning, the bolt hole 9, which is desirably somewhat elongated or slotted, comes opposite the flange of vertical support member S, Fig. 6. Screws 11 through these openings carry the weight of the face plate and secure it in vertical relation to the supports in desired position. With the screws removed, the face plate can be bodily dis-assembled from the vertical supports by moving the face plate up or down with respect to the supports, locking engagement being had by means of lugs 13, Figs. 5 and 7, projecting on the inside of the reinforcing member 24 which has been secured to the face plate the lug being near the edge opposite the vertical support, and positioned for instance desirably at a point intermediate the ends of the panel. It is of course possible to affix the lugs 13 to the rear surface of the face plates but in this case the reinforcing member 24 must be shortened so as to avoid contact with vertical supports S. The lugs 13 being slightly undercut or bent over, may enter an adjacent opening in the flange of the vertical support S at either the upper or lower end

of the opening in such flange, these being the widest portions and from thence the opening narrows to its center, whereby the lugs 13 are closely engaged, being raised or lowered to such position, as shown in Fig. 7. Conversely, removal of the plate is effected by either raising or lowering to bring the lugs 13 into the enlarged upper or lower end of the slot in the flange whereupon the plate can be bodily swung away from the vertical support. Referring now to Fig. 6 it will be seen that each support S is suitably anchored to the floor, by means of a narrow stilt 15 between the support and the floor. The stilt being secured by screws 16, the support is firmly held, while at the same time amplified space between the stilt 15 and the baseboard which is suitably secured by any desired means to cover the lower edge of the face plates, permits laying in of pipes of considerable size in addition to wires etc. The wings 8 of the corner brackets of the face plates being in opposed position on assembled adjacent face plates, Figs. 2, 6, it is seen that take-up screws or bolts 18, see Fig. 8, through the holes 19 of the opposed wings permits the drawing up of the edges into tight joint fit. The brackets B being sufficiently exposed above and below the plates, such adjustment and tightening may be readily accomplished. Any desired vertical adjustment is obtained by reason of the lee-way afforded by the engagement of the lug 13 with the slot in the support, whereupon the screws 11 may be tightened into final holding position, and the baseboard 20 is put in place thereover, its detail being immaterial to the present invention. And, the upper exposed ends are closed by members referred to more in detail hereinafter. It is to be understood that the vertical adjustment takes place prior to the insertion of the screw 11 and not afterward. Thus it will be seen that the plates are firmly held to the supports S but are capable of movement up and down so as to aline slots 9 with the corresponding holes in the vertical supports.

The wall section being of spaced-apart plates, insulating filling material, as mineral wool etc., can advantageously be provided as illustrated diagrammatically at F, Fig. 2. Possible deformation of the face plates in handling may be prevented by the provision of angle section or channel section transverse reinforcements 24, Figs. 1, 2 and 5, and to better assist in the holding up of the mineral wool or the like, angular prongs 25, Fig. 5, are desirably provided at spaced intervals. The upper edges 26 of these prongs are blunt and desirably square.

Where a door is incorporated in the section, a floating and an adjustable mounting may be had by means of door frame member 28, Fig. 12, for the hinging and strikes, and these are adjustably secured to the auxiliary vertical supports 29 by take-up screws 30 between the web of the auxiliary vertical support and the web 31 of the door frame member. By means of a keyhole slotted type of opening in the web of the auxiliary vertical support 29, Fig. 13, the head of the bolt or screw 30 can be conveniently put through the enlarged portion of the opening and be tightened against the narrowed portion of the slot. It will be seen thus that the door may be hung on its framing in place, and any compensation or stress may be taken care of by the adjustable bolts 30 at their different locations, and a smoothly closing door is readily obtainable. Subsequently if at any time binding develops at some point, compensating adjustment may be easily had by

the adjusting screws 30. It will be understood that the door trim is removable in accordance with well known practice, this being no part of the present invention, the space between the vertical supports and the door frame members being thereby made accessible. Passageways are provided at both sides of the door from floor to ceiling and over the door for wires, piping, etc., and by means of a narrower connector bar 32, Figs. 9, 10 and 11, the lower vertical support section 31 and the upper support section S' are well secured, while amplified space around the bar 32 accommodates it to size not heretofore applicable.

The door frame is three-sided and the top strike or jamb, see Fig. 10, is similar to hinge and lock strikes 28. These members 28 are secured to the supports 29 by bolts passing through slotted holes in the supports into tapped plates secured in the strike 28. The detail of these connections is not illustrated but the principle is disclosed in the patent, No. 1,981,538. Thus we have a door frame unit consisting of vertical supports, a fixed panel above the door in which an operating transom can be installed, and a door frame which is vertically adjustable with respect to the supports in order to compensate for variations in floor level or thickness of floor coverings.

A removable picture mold provides placement for picture hooks and also allows access to the space behind for wiring, piping, etc., and as shown in Fig. 14 this may involve a removable member 35 held by clips 36. The latter can be introduced into the mold section by sliding into position from the end when exposed, the clips riding behind the upstanding edge of the face plate of the panel. The mold section 35 is provided with a recess or groove 37 and a hook-holding lip 38. Where the partition sections extend to the ceiling, as in Fig. 14, the mold member 35 serves to also cover the free margin of the upper filler plate 40 which is secured to the ceiling, and a neat unobtrusive finish is had. Behind the picture mold is space for wiring, accessible also for wiring entering at any point along the ceiling. The picture mold is also capable of covering considerable variations in the spacing between the ceiling member and the upper edge of the face plates of the panel sections, and it will be noticed that the mold has load-bearing support on the panel units. By reason of the arrangement of the clips, sufficient up and down sliding movement with respect to the flange of the ceiling member may be had to permit the mold to be removed by raising sufficiently so that the lower engagement can be cleared past the upper edge of the face plate and the mold then be tilted outwardly and thus be taken off. A slightly variant finish of the picture mold may omit the groove along the face and the picture hooks may be hung on the upper edge 38'. Where it is desired to leave a space between the ceiling and the upper edge of the partition, the picture mold 35 similarly held by the clips covers the upper margin of the panel face plate 3, Fig. 15, and a finish for the top may be had by the channel member 42 which has laterally extending flanges 43 and rebent flanges 44 engaging the upper margins 48 on the picture mold. A deeper channel member 45 has its flanges 48 secured suitably, as by welding, to the flange portions 43 of the channel member 42. Holes 46, 47, in the channel members allow access for wires etc. or a screwdriver for operation on screws through convenient holes as at 47.

Other modes of applying the principle of the invention may be employed, change being made as regards the details described, provided the features stated in any of the following claims, or the equivalent of such, be employed.

We therefore particularly point out and distinctly claim as our invention:

1. In a wall construction, channel vertical supports, panel face members, openings in the lateral wings of said channel vertical supports, said openings being wider at the ends than at the middle, locking lugs projecting inwardly from each face member and effectively interlocked with said vertical supports in said openings and screw-threaded means for also tightening a face member on its vertical support to prevent vertical movement.

2. In wall construction, channel vertical supports, panel face members, openings in the lateral wings of said channel vertical supports, said openings being wider at the ends than at the middle, and locking lugs projecting inwardly from each face member and interlocked in said openings.

3. In wall construction, vertical supports, panel face members, and means including cooperating locking lugs and receiving openings in said supports and face members, said openings tapering in opposite directions, in such manner that the ends are larger than the center, for permitting disassembly of a panel face member from a vertical support by either raising or lowering the face member.

4. In wall construction, panel sections including a channel vertical support for each edge of the section and with the channel webs in the section directed back toward back, panel face members, openings in the flanges of said vertical supports, said openings being wider at the ends than at the middle, locking lugs projecting inwardly from each face member interlocked in said openings, corner brackets on the inside of said face members extending slightly therebeyond at the top and bottom, each having one wing provided with a slotted fastener-receiving opening, fasteners passing through said openings securing said face members to the vertical supports, each of said brackets having another wing at right angles provided with a fastener-receiving opening and fasteners extending through said openings for securing adjacent face members edge to edge.

5. In wall construction, a panel face member, a panel corner bracket near each corner thereof, each of said brackets having two wings, one wing spaced from and parallel to the plane of the panel and extending toward an opposite corner and another wing at right angles to said first wing and extending toward said panel, and openings in such wings for fastening means.

6. In wall construction, vertical supports, a panel face member, and angle-wing pieces, one of said pieces being secured to said panel face member near each corner thereof and each of 5 said angle wing pieces having openings for the reception of connecting means, said means extending to an adjacent vertical support, each of said angle wing pieces having one wing spaced from and parallel to the plane of the panel and 10 extending toward an opposite corner and another wing at right angles to said first wing and extending toward said panel, and openings in such wings for fastening means.
7. In wall construction, vertically extending 15 post members, panel face members mounted upon said posts, said panel members having horizontally slotted brackets and fasteners extending through such slots for fastening the panel members to the posts, and means independent of the vertical supports for drawing adjacent face members in tight edge to edge contact.
8. In wall construction, vertical supports, a door frame and panel face members thereabove, and a narrow bar extending from said door frame 20 for supporting upper structure and connected to a vertical support adjacent a face member above said door frame, said support being spaced from said door frame thereby providing passway space across the top of the door frame.
9. In wall construction, a panel face member, a horizontal re-inforcing member on said panel face member, and upwardly directed prongs on the inside of said re-inforcing member and extending away from same for anchoring filling material, said prongs having free, square ends. 25
10. In wall construction, vertical supports, panel face members, a horizontal picture mold member having a longitudinal groove, clips at the back for holding said member, and a cornice finish including a deep channel member with upwardly extending flanges and a shallow channel member seated within said first member and having outwardly extending flanges, said last named flanges having down turned portions, one 30 of said portions engaging the inner upper margin of said mold member.
11. In a wall construction, panel sections erectable as units, each section comprising a vertical support for each edge of the section, panel face 35 members secured to said vertical supports by bracket members, said securing means carrying the weight of said panel face members, and take up means engaging each pair of adjacent bracket members to draw up the edges of adjacent face members into a tight joint fit.

GILBERT L. FOWLES.
CHARLES J. NOCAR.
